UNITED STATES PATENT OFFICE

PAUL R. SIGSBEE, OF WILBRAHAM, MASSACHUSETTS, ASSIGNOR TO SAMUEL H. CAMP,
DOING BUSINESS AS S. H. CAMP & COMPANY, OF JACKSON, MICHIGAN

ABDOMINAL SUPPORT

Application filed February 6, 1929. Serial No. 337,957.

This invention relates to abdominal supports and has as an object the provision of a garment having a relatively rigid reinforcing member adapted to localize the pressure of the garment and having means for directly adjusting the pressure of the reinforcing member preferably without transmitting the pull on the member through the garment.

Other objects and advantages of the invention will become more apparent as the following description proceeds, particularly when reference is had to the accompanying drawings, wherein

Figure 1 is a back plan view of a garment in extended position showing the invention applied to the same,

Figure 2 is an enlarged front plan view of a portion of the garment shown in Figure 1,

Figure 3 is an enlarged plan view of the reinforcing member shown in Figure 1, part of the structure being broken away to more clearly bring out the details of construction,

Figure 4 is an enlarged sectional view taken substantially on the lines 4—4 of Figure 3, and

Figure 5 is a view similar to Figure 1 showing a slightly modified form of construction.

Referring then particularly to the drawings wherein like reference characters designate corresponding parts throughout all views, there is illustrated in Figure 1 a belt or abdominal support formed of two sections 10 and 11, which are connected at the back by the lacing 12. At the front the sections are connected by quick detachment means such as the loops 13 and hooks 14.

Associated with the front of the belt or garment is a reinforcing member 15 adapted to accentuate the pressure of the garment over a predetermined area. This member is of a stiffer material than the body of the garment and may as illustrated, be formed as a pad of light sheet metal inclosed in a cloth cover 16. The reinforcing member is formed

in sections and includes a center section 17 and the end or side sections 18 and 18' hinged to the center section as at 19. Thus by properly moving the end sections relative to the center section, the pressure of the pad may be evenly distributed over an extended area.

In order that the pressure of the reinforcing member may be adjusted without transmitting the pull on the same through the garment, suitable strap members 20, 40, 41 and 42 respectively are provided. As shown the strap 20 bridges the gap between the sections 10 and 11 and is provided at its opposite ends with buckles 25. The straps 40 and 41 are secured to and extend from the buckles 25 over the sections 10 and 11 respectively. The strap 41 extends through a slot 22 in the hinge section 18' of the reinforcing member, and is stitched to the center section 17. The strap 40 is provided with hooks 24; and the strap 42 is stitched to the section 17 of the reinforcing member, extends through a slot 22' in the section 18 of the reinforcing member and is provided at its free end with loops 23. Thus when the straps are tightened, pressure will be applied not only to the center section 17 of the pad, but also to the hinged sections 18 and 18' thereof. The buckles 25 enable the straps to be adjusted to increase or decrease the pressure exerted by the reinforcing member.

As illustrated the reinforcing member may be loosely held in position in the front of the garment by tapes 26 stitched to the garment. These tapes cooperate to form a pocket which loosely receives the reinforcing member, whereby the latter is freely movable for adjustment relative to the garment.

The adjusting straps may as illustrated in Figure 1, be entirely free from connection with the garment except where they pass through suitable guiding loops 27 secured to the face of the garment whereby the reinforcing members may be adjusted to any degree desired without in any way varying the adjustment of the garment.

If desired, as illustrated, the adjusting straps may cooperate with the back lacing 30 to adjust the latter in the manner described in the patent to S. H. Camp No. 1,438,942, issued December 19, 1922. Referring to Figure 5 it will be noted that each adjusting buckle 25' is provided with eyelets 28 and that the adjacent edges of the sections 10' and 11' are provided with the eyelets 29.

The lacing 30 is extended from the buckle 25' carried by the section 10 through the eyelets 29 of the section 11, then through the eyelets 29 of the section 10' and then to the buckle 25' carried by the section 11'. This is continued until the lacing has been extended through all of the eyelets in the manner illustrated, resulting in the production of a leverage whereby a movement of the straps is converted into a relatively lesser movement of the garment sections. Thus a tightening of the straps will increase the pressure of the reinforcing member and will simultaneously tighten the garment to a lesser degree.

From the above, it is believed that the structure and use of the invention will be readily apparent. The reinforcing member 15 will function to localize the pressure of the garment to the area of the body where the greatest support is needed. The reinforcing member may be moved relative to the garment so that the same may be located at any point desired and the pressure of the reinforcing member may be directly increased by virtue of the fact that the adjusting straps are secured directly to this member. The hinged end sections of the reinforcing member permit an even distribution of pressure by this member, whereby pressure may be evenly applied over an extended area.

While the reinforcing member has been illustrated as being loosely associated with the garment by virtue of tape-like members, it will be readily apparent that numerous other ways might be provided for loosely maintaining the reinforcing member in position. Further if desired, the reinforcing member might be sewed directly to the garment and the adjusting straps afterwards secured to the reinforcing member. Also while the reinforcing member has been shown as being applied to an abdominal support or the like, it is obvious that the same may be associated with a garment of any character whatsoever. The right is therefore reserved to make such changes in the details of construction and arrangement of parts as will fall within the purview of the attached claims.

What I claim as my invention is:

1. An abdominal support comprising a garment, a reinforcing member associated with said garment for accentuating the pressure thereof over a predetermined area, said reinforcing member being formed in sections of material stiffer than the body of said garment, said sections being movable with respect to each other, and an adjustable strap secured to one of said sections at approximately the center thereof and extending through another of said sections for directly adjusting the pressure of said reinforcing member.

2. An abdominal support comprising a garment, a relatively rigid pad associated with said garment for accentuating the pressure thereof over a predetermined area, said pad including a center section and hinged side sections, and oppositely extending adjusting straps secured to the center section of said pad, one of said straps passing through each of said hinged side sections, whereby the pressure of said pad may be directly adjusted.

3. An abdominal support comprising a body encircling garment and means associated with said garment for exerting an additional pressure on the body of the wearer over a predetermined area, said means including a, relatively stiff pad arranged between the front of the garment and the body of the wearer, said pad being adapted for floating movement relative to the garment whereby movement of the garment will not vary the position of the pad relative to the body of the wearer, and means for adjusting the pressure exerted on the body of the wearer by said pad, including straps secured to said pad at the center thereof and extending through said pad at opposite ends thereof.

4. An abdominal support comprising a body encircling garment and means associated with said garment for exerting an additional pressure on the body of the wearer over a predetermined area, said means including a relatively stiff pad arranged between the front of said garment and the body of the wearer, said pad being adapted for floating movement relative to the garment whereby movement of the garment will not vary the position of the said pad relative to the body of the wearer, and straps connected directly to said pad at the center thereof and extending through the pad adjacent opposite ends thereof for adjusting the pressure exerted by the same on the body of the wearer without transmitting the pull through the said garment.

5. An abdominal support comprising a garment, a relatively rigid reinforcement loosely mounted on a portion of the garment and having a central portion and wing portions hingedly connected to said central portion, and means loose with respect to the garment for exerting a pull on the reinforcement, including straps terminally secured to the central portion and extending through slots in the wing portions.

6. An abdominal support comprising a garment having sections and embracing the body, a relatively rigid reinforcement loose with respect to the garment, and means for adjusting the reinforcement relative to the garment to increase the pressure exerted by the reinforcement and without transmitting a pull through the garment, including a flexible element bridging the gap between the garment sections and provided at opposite

ends with buckles, a strap secured to the reinforcing member at the center thereof, and extending through said member at one end thereof, and straps secured to said buckles and extending over said sections, one of said last mentioned straps extending through the reinforcing member and being secured thereto adjacent the center thereof, the other of said last mentioned straps being detachably secured to the first mentioned strap.

10 In testimony whereof I affix my signature.
PAUL R. SIGSBEE.
